REPERTORY DIALER TELEPHONE HOUSING

James N. Burlin, New York, N.Y., and Stanley E. Seretny,
Indianapolis, Ind., assignors to Bell Telephone Laboratories,
Incorporated, New York, N.Y., a corporation of
New York

Filed Nov. 5, 1963, Ser. No. 77,297

Term of patent 14 years

(Cl. D26—14)

FIG. 1

FIG. 2

FIG. 6

FIG. 3

FIG. 4

FIG. 5

FIG. 1 is a left side, top and front perspective view of a repertory dialer telephone housing;

FIG. 2 is a top plan view;

FIG. 3 is a right side elevational view;

FIG. 4 is a left side elevational view thereof;

FIG. 5 is a rear elevational view thereof; and FIG. 6 is a fragmentary cross-sectional view thereof, taken on line 6-6 in FIG. 2.

We claim:

The ornamental design for a repertory dialer telephone housing, substantially as shown and described.
